CLAIM

The ornamental design for a transparent bag packed with different colored balls of cotton candy, as shown and described.

DESCRIPTION

FIG. 1 is a perspective view of package of cotton candy balls showing my new design;

FIG. 2 is a side elevation view thereof, the opposite side being a mirror image;

FIG. 3 is a front elevation view thereof, the opposite side being a mirror image;

FIG. 4 is a top plan view thereof; and,

FIG. 5 is a bottom plan view thereof.

The cotton candy balls are lined to represent color.
